UNITED STATES PATENT OFFICE.

JULIUS S. MEYER, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 13,674, dated February 27, 1883.

Application filed January 25, 1883. Term of patent 3½ years.

To all whom it may concern:

Be it known that I, JULIUS S. MEYER, of New York city, in the county of Westchester and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The ground *a* is a plain ground, with an irregular ornament, resembling fret-work, running prominently over it. On this ground are disposed two large flower and leaf groups, *A* and *B*, and two smaller similar groups, *C* and *D*, each consisting of a central mass of open flowers and leaves, surrounded by blossom and fern sprays springing out in all directions, as is clearly shown in the photograph.

I claim—

1. The design for a ground for a carpet, consisting of the ground *a*, substantially as shown and described. 25
2. The design for a carpet, consisting of the group *A*, substantially as shown and described.
3. The design for a carpet, consisting of the group *B*, substantially as shown and described.
4. The design for a carpet, consisting of the group *C*, substantially as shown and described. 30
5. The design for a carpet, consisting of the group *D*, substantially as shown and described.
6. The design for a carpet, consisting of the groups *A*, *B*, *C*, and *D*, substantially as shown 35 and described.
7. The design for a carpet, consisting of the groups *A*, *B*, *C*, and *D* and the ground *a*, substantially as shown and described.

JULIUS S. MEYER.
